CLAIM

The ornamental design for an interface for dental model articulator adaptor, as shown and described.

DESCRIPTION

FIG. 1 is a top perspective view of an interface for dental model articulator adaptor, showing our new design; FIG. 2 is a front elevational view of the interface of FIG. 1; FIG. 3 is a back elevational view of the interface of FIG. 1; FIG. 4 is a left elevational view of the interface of FIG. 1; FIG. 5 is a right elevational view of the interface of FIG. 1; FIG. 6 is a top plan view of the interface of FIG. 1; and, FIG. 7 is a bottom plan view of the interface of FIG. 1. The base component shown in broken lines is unclaimed environment and forms no part of the claimed design.
